HENRY V. DEEMAR, OF ST. LOUIS, MISSOURI, ASSIGNOR OF ONE-HALF TO HERBERT H. DEEMAR, OF LOS ANGELES, CALIFORNIA.

AIR CIRCULATOR AND HEATER.

Application filed May 18, 1927. Serial No. 192,349.

This invention relates to a heater for homes and other places in which either gas or electricity may be employed as the heating medium.

- 5 A primary object of the invention is to so construct a heater of this character that it will radiate heat and at the same time circulate fresh air, either with or without the aid of a blower.
- 10 Another object is to provide a heater having hollow stand pipes for the passage of fresh air therethrough and which is equipped with means for heating the air in these pipes without contaminating it.
- 15 In carrying out these objects, the invention is susceptible of modification without departing from the spirit or sacrificing any of the advantages of the claimed invention; there being shown in the drawings for illustrative purposes, certain preferred and practical forms in which;

Figure 1 represents a vertical section of a heater constructed in accordance with this invention, and in which a gas burner is employed, as the heating element,

Fig. 2 is a horizontal section taken on the line 2—2 of Fig. 1,

Fig. 3 is a transverse section taken on the line 3—3 of Fig. 1,

30 Fig. 4 is a view similar to Fig. 1, with a blower shown used in connection therewith for passing the fresh air through the stand pipes,

Fig. 5 is a transverse section taken on the line 5—5 of Fig. 4,

Fig. 6 is a detail sectional view taken on the line 6—6 of Fig. 4,

Fig. 7 is a vertical section, with electric heating coils shown as the heating medium,

40 Fig. 8 is a horizontal section taken on the line 8—8 of Fig. 7, and

Fig. 9 is a diagrammatic view showing the arrangement of the heating coils in groups and the means for controlling them.

45 In the embodiment illustrated in Figs. 1 to 3, a casing 1 is shown composed of sheet iron and which may be of any desired cross sectional configuration, being here shown cylindrical. This casing 1 is supported by

50 legs 2, mounted on an annular frame 3 which supports above it a fuel mixing chamber, the bottom of which is apertured to receive

air pipes 4 which extend up into a plurality of hollow stand pipes 10 which extend through the casing 1 and are preferably arranged concentric therewith as shown in Figs. 2 and 3, and which will be hereinafter more fully described. Other air pipes 5 also extend upward from the bottom of the mixing chamber and are arranged in connection with burners 15 and supply air which is commingled with a fuel mixture entering at the side of the heater through a feed pipe 17, said feed pipe being equipped with a baffle 18 in the form of a screen for 65 breaking up the fuel before its entrance into the mixing chamber. The fuel supply pipe 17 has a mixing nozzle located at its outer end composed of an outer casing 19 through which gas is fed and an inner 70 casing 19^a of smaller diameter than the casing 19, both of which have tapered nozzles at their discharge ends and through which air and gas are discharged into the pipe 17. A gas supply pipe 7 opens into the casing 75 19 through one side wall thereof and is provided with a cut-off cock 8 for controlling the supply of gas thereto while a valve 9 controls the air entering through casing 19^a.

80 A flame shell 20 is arranged within the casing 1 concentric therewith, being spaced slightly therefrom to provide between it and said casing an air space or chamber 21 which is supplied with air by means of a plurality of tubes 6 extending upwardly through the 85 mixing chamber and discharging into the chamber 21. The top 1^a of the casing 1 is provided outside the openings through which the stand pipes 10 pass with a plurality of apertures 21^a which communicate 90 with the chamber 21 and through which the heated air from said chamber is discharged. The flame shell 20 shields the casing 1 from the flame of the burner, and protects the enamelling or finish of the casing while the 95 space between the casing and the shell affords additional heating surface and increases the hot air heating capacity.

100 Any desired number of hot air or stand pipes 10 may be employed, sixteen being here shown. These pipes extend through the mixing chamber of the burner to and through the top plate 1^a of the casing 1, the air entering the pipes 10 through the pipes

4 and travelling upward through the pipes 10 becoming heated in its passage passes out of the upper end of the heater, as shown by the arrows. This air, in its travel, does not mix with any fumes at any point throughout the apparatus. These stand pipes 10 which are shown perpendicular may be made of any appropriate desired shape.

- 10 Arranged within the space which is encircled by the stand pipes 10 is a shell 22 open at its top and closed at its bottom and with its open upper end spaced from the top 1^a and the casing 1, as is shown clearly in Fig. 1. Located within the shell 22 is a fume pipe 23 which extends from a point spaced from the bottom of shell 22 up through said shell and through the top 1^a where it discharges into a pipe or other exit 24. As shown in the drawing the pipe 24 is equipped with a fume diffusing cap 25. The arrangement of the fume pipe 23 and shell 22 produces a down draft for the products of combustion as is shown by the arrows b.

An annular bottom plate 10^a is arranged at the lower end of the casing 1 and apertured for the passage therethrough of the stand pipes 10 and the tubes 6 the open central portion 10^b of which is arranged directly over the burners so that the flames therefrom will pass up through this opening into the interior of the flame shell.

In the forms shown in Fig. 4, the structure of the heater is the same except that a blower 30 is used for forcing fresh air up through the standpipes 10 and the tubes 6 said blower being equipped with a discharge member 31 with its upper end encompassing the lower end of the stand pipes and the pipes 5 which supply air to the burners 15. The blower 30 may be operated by any suitable means, not shown.

In the form shown in Fig. 7, electric heating coils are used for the heating medium instead of the gas burners 15 shown in the other figures. In this form of the invention the casing 1' is similar to that shown in the other figures and is mounted on a hollow base 2' which may be provided either with a blower or not, as desired, the blower in this instance being similar to that shown at 30 in Fig. 4.

Arranged within the space which is encircled by the stand pipes 10' are a plurality of electric heating coils here shown arranged in three groups, numbered 32, 33 and 34. Four coils are here shown in each group and each group is arranged within a circuit controlled by a switch or plug 35, here shown carried by a three way socket 36. It will thus be seen that each group of heating coils or resistances are independent one of the other and may be controlled independently so that one group may be turned on when

the weather is moderate and when more heat is required, the second group will be turned on, and when still further heat is wanted, the third group may be turned on. This heating of the resistance coils will operate in the same manner as the burners 15 which are shown in the other figures, to heat the air within the casing 1' and then passing up through the stand pipes 10'.

The top 37 is provided with an upstanding flange 38 adjacent its periphery which supports a dome-shaped wire net covering 39 designed to protect the stand pipes and prevent insects and articles from dropping down into them. At the apex of this cover 39 is a collared opening 40 for the entrance of the wires W which supply the current for the heating coils.

From the above description, it will be obvious that in any of the forms illustrated, the heater will operate to supply heat by radiation, as well as to discharge heated air therefrom, and also to circulate fresh air into the room in connection with which it is used.

It will be obvious that when a blower is not used to force fresh air through the heater, the air which is heated in the stand pipes will rise causing a circulation of fresh air up through the heater.

Without further description, it is thought that the features and advantages of the invention will be readily apparent to those skilled in the art, and it will of course be understood that changes in the form, proportion and minor details of construction may be resorted to, without departing from the spirit of the invention or its scope as claimed.

I claim:—

1. A heater of the class described comprising a cylindrical casing closed at its top and having an annular closure at its bottom, a flame shell arranged concentrically within said casing and spaced therefrom, said shell extending parallel with the entire length of the casing, fresh air supply tubes opening through the bottom of the casing between it and the flame shell, the top of the casing between it and the flame shell being provided with apertures for the outlet of the air, stand pipes extending longitudinally within said flame shell and opening through the top thereof and extending below the bottom, and means for heating the interior of the casing including the air passing through the stand pipes.

2. A heater of the class described comprising a casing closed at its top and having an annular bottom providing an opening therein disposed over a heating unit, a flame shell arranged concentrically within said casing and extending parallel with the length thereof and spaced therefrom to provide an air space between it and the casing,

a plurality of tubes extending upwardly through the bottom of the casing and discharging into the space between the casing and the flame shell, the top of said casing having outlet openings leading from the space between the casing and the shell, a shell mounted in said flame shell which is open at its top and closed at its bottom, the open upper end thereof being spaced from the top of the casing, and a fumes pipe extending through the top of said casing into said last-mentioned shell to a point near the bottom thereof. 10

HENRY V. DEEMAR.
